COMBINED GAME BOARD AND CHIP HOLDER
OR THE LIKE

Don W. Kester, 5125 S. Medley Court,
Seattle, Wash. 98118

Filed Nov. 23, 1970, Ser. No. 26,112

Term of patent 14 years

Int. Cl. D21—01

U.S. Cl. D34—5

FIG. 1 is an isometric view of a combined game board and chip holder or the like, showing the external portions of the new design.

FIG. 2 is an isometric view thereof showing the internal portions of the new design.

FIG. 3 is a plan view of the game board face of either half thereof, the game boards faces of the two parts being identical.

FIG. 4 is an elevational view of one side thereof the opposite sides being identical.

FIG. 5 is a plan view of the top (or bottom) thereof, the top and bottom being identical.

FIG. 6 is an elevational view of one end thereof, the ends being identical.

I claim:

The ornamental design for a combined game board and chip holder or the like, as shown and described.
